UNITED STATES PATENT OFFICE.

EDOUARD BINARD, OF BRUSSELS, BELGIUM.

HIGH-FREQUENCY SELF-INDUCTION COIL.

Application filed August 27, 1921. Serial No. 495,964.

To all whom it may concern:

Be it known that I, EDOUARD BINARD, a subject of the King of the Belgians, residing at Brussels, in the Kingdom of Belgium, ⁵ have invented certain new and useful Improvements in High-Frequency Self-Induction Coils (for which I have filed an application in Belgium, Aug. 10, 1920), of which the following is a specification.

10 This invention relates to a new method of winding self-induction coils for currents of high frequency, of the kind in which the adjacent windings are disposed on a flat core, such, for instance, as one furnished with ¹⁵ radially disposed grooves, and in such manner that the wires cross in these grooves.

The object of the invention is to enable a coil of this kind to have the greatest possible number of turns on the core so that, ²⁰ for equal resistance, and whilst employing the same quantity of winding wire, the self-induction obtained is much greater than has heretofore been attainable.

The result is obtained, according to this ²⁵ invention, by causing the conductor, constituting the winding, instead of passing from one notch or gap to the next notch, as has heretofore been customary to pass to a notch further removed. Under these conditions the wire on one face of the supporting core traverses successively in front of several notches or gaps before passing through a notch to the other side of the core. The total number of the notches is ³⁰ preferably so chosen that it comprises one notch more or less than a multiple of the number of notches forming the winding step, so that after winding a number of turns equal to the number of the spaces passed over, the ³⁵ wire will have passed through all the notches.

By reason of this method of winding, the wires belonging to the different coils take, at each winding step, the form of a chord of an arc corresponding in length to the spaces ⁴⁰ between the notches and arrange themselves on the two faces of the core in such manner as to slightly increase the width of the core, but to considerably reduce its diameter as compared with other coils.

50 The accompanying drawings show, by way of example, a method of carrying out the invention.

Fig. 1 is a view, in elevation, of a disc of insulating material employed in conformity ⁵⁵ with the invention for the construction of the core.

Fig. 2 shows, diagrammatically the method of winding.

As shown in Fig. 1 for the purpose of winding the coils instead of using an insulated core or plate provided with needles or guiding pins for effecting the winding, which are removed after the completion of the winding, and immersing the latter in an insulating substance such as paraffin for example, as is customary, according to this invention a thin disc *a* of insulating material is used in which notches *b* are cut, preferably radially, thus forming projections or teeth *c*. ⁶⁰

The insulated wire or the table *d* which is to constitute the winding, is passed, by means of a coil winding machine for example, through a first notch *1* and is then passed over the face of the disc *a* past a certain number of teeth *c* and notches *b* before it passes up through another notch *b* to the other face of the disc. In the example shown a winding "step" has been chosen, which comprises three teeth (or three notches), hence the wire or cable passes to the rear of the teeth *c* marked 1, 2, 3. It then passes through the notch *b*, marked 4, on to the rear face of the disc before passing over the front faces of the teeth 4, 5, 6, in order to again pass to the rear of the disc through the notch 7, and so on. The total number of the notches or of the teeth is determined in the example shown, so as to be a multiple of the number of notches or of the teeth, constituting the number of teeth passed over plus or minus one; it being evident that after winding a complete turn the wire will pass from one side to the other of the disc *a* through the notch which precedes or follows immediately the notch from which the preceding winding commenced. ⁷⁰

By reason of this disposition, the point where the wire or cable of two successive windings crosses, is displaced every time by one notch, and, owing to the length of the step, the wire takes the form of a chord of an arc corresponding in length to the step, it is evident that the different turns will arrange themselves on the two faces of the supporting disc, thus producing a coil of small diameter, but having considerable thickness inasmuch as it has teeth and notches in its coils. ⁸⁰

In Fig. 2, to clearly illustrate the invention, it has been supposed that the wire is ⁹⁰ wound in a circular manner between the notches, but it is evident that in practice,

owing to the tension of the wire, it takes, as before stated, a straight path across the notches or teeth which it passes over, as is shown for example by the dotted lines at *e*.

5 In the example shown, the total number of slots or teeth is a multiple of the number of teeth, constituting the step augmented or diminished by one, but it is evident that the method of winding specified can be modified, the only essential condition for obtaining the filling of all of the slots being that the total number of slots or teeth are multiples of the number of slots or teeth comprising a step.

10 15 What I claim is:

1. A high frequency self-induction coil comprising a form provided with radially disposed slots and a winding thereon, the wire of which winding passes alternatively over and under more than one slot before 20 passing through a slot to the other side of the plate.

2. A high frequency self-induction coil comprising a form provided with radially

disposed slots and a winding thereon, the 25 wire of which winding passes alternatively over and under more than one slot before passing through a slot to the other side of the plate, the total number of slots of the plate through which the wires pass being one 30 or less than a multiple of the slots passed to form a winding step.

3. A high frequency self-induction coil comprising a form provided with a plurality of slots forming teeth between them, and 35 a wire passing through said slots alternately from face to face of the form and extending past a plurality of the teeth at each stretch on each face before passing through a slot to the opposite face, with the turns at intervals 40 passing through slots between those through which the preceding turns passed.

In testimony whereof I have affixed my signature in presence of two witnesses.

EDOUARD BINARD.
